(57) **CLAIM**

The ornamental design for a display screen portion with graphical user interface, as shown and described.

DESCRIPTION

The present application is related to U.S. Design patent application Ser. No. 29/623,813, U.S. Design patent application Ser. No. 29/623,844, U.S. Design patent application Ser. No. 29/623,815, U.S. Design patent application Ser. No. 29/623,820, and U.S. Design patent application Ser. No. 29/623,833, filed concurrently herewith, the entire disclosures of which are incorporated herein by reference.

FIG. 1 is a front view of a first image of a display screen portion with graphical user interface according to our design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof; and,

FIG. 11 is an eleventh image thereof.

The broken lines that are contiguous with the edges of gray stippling show interior boundaries of the claimed design and form no part thereof. The dash-dot broken lines illustrate the perimeter of an underlying display screen portion and the bounds of the claimed design. The dash-dot broken lines form no part of the claimed design.
